CLAIM

The ornamental design for a space ship-shaped pasta, as shown and described.

DESCRIPTION

FIG. 1 is a front elevational view of space ship-shaped pasta showing our new design, the undisclosed rear being a mirror image;

FIG. 2 is a top plan view thereof, the undisclosed bottom being a mirror image;

FIG. 3 is a left side elevational view thereof; and

FIG. 4 is a right side elevational view thereof.

FIG. 2

FIG. 3

FIG. 1

FIG. 4
